UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

1,409,428.

Specification of Letters Patent. Patented Mar. 14, 1922.

Application filed June 4, 1921. Serial No. 475,016.

To all whom it may concern:

Be it known that I, EDWARD S. STIMPSON, a citizen of the United States, residing at Hopedale, in the county of Worcester and 5 State of Massachusetts, have invented an Improvement in Warp Stop Motions for Looms, of which the following description, in connection with the accompanying drawings, is a specification, like characters on the 10 drawings representing like parts.

This invention relates to warp stop mechanisms for looms, whereby the loom is brought to rest when a warp thread becomes broken or unduly slack.

15 Where the main portion of the warp stop motion is supported between the rear of the loom and the heddles, it is desirable that the construction and operation of the warp stop motion be such as not to interfere with the 20 size of the warp beam or the amount of warp wound on the beam, and that the fore and aft dimensions of the warp stop motion proper be such as for ready application to the loom between the warp beam and 25 heddles.

One of the objects of the present invention is to provide a warp stop motion which shall be simple in construction, efficient in 30 operation, and wherein the parts shall be so combined and related as to avoid interference with the size of the warp beam and enable the warp stop motion to be placed between the rear of the loom and the heddles.

In carrying the present invention into 35 practical effect, the feelers are supported by separate feeler carriers and extend transversely of the loom above the plane of the warp threads. The feeler carriers are given a reciprocating movement simultaneously in 40 opposite directions.

Other objects of the invention and novel features and combination of parts will hereinafter be described in connection with the accompanying drawings which show one 45 good, practical form of the invention.

In the drawings:

Figure 1 is a sectional side elevation of a portion of the loom containing the present invention;

50 Fig. 2 is an enlarged detached perspective view of the main portions of a warp stop motion, portions of which are broken away;

Fig. 3 is a perspective view of the warp stop motion proper, showing the two feeler 55 carriers raised from operative position, so

that the loom may be run without stopping due to a fault in the warp; and

Fig. 4 is an enlarged detached elevation showing the two feeler carriers.

The loom frame 1 has mounted at the rear 60 portion thereof the warp beam 2, as usual, and mounted between the rear of the loom and the heddles is the main portion of the warp stop motion which is connected by a train of mechanism to means for stopping 65 the loom when a warp thread becomes broken or too slack. The train of mechanism for transmitting the stopping movement to the loom may be variously constructed, but as shown in Fig. 1, the shipper 3, which is 70 normally held in the shipper notch during the running of the loom, is detached from such notch by a train of transmission mechanism when a warp fault occurs.

The shipper 3 is pivotally mounted at 4 75 and resting against the shipper is an arm 5 of a lever pivoted to the loom frame at 6 and connected by a link 7 with means for turning the lever to detach the shipper from its holding notch on the backward movement 80 of the lay after the occurrence of a warp fault.

As indicated in Figs. 1 and 3, the rear end portion of the link 7 is connected at 8 with an arm 9 pivotally supported at 10 by a 85 bracket 11. The arm 9 also carries the dog 12 provided with a pin 13 which engages a controller 14 secured to a rocker 15 supported by the loom side or bracket 11. The controller 14 is provided with a slot in which 90 the pin 13 may move toward and from the front of the loom. The lay 16 carries a bunter 17 which, when the dog 12 is moved into position to effect loom stoppage, engages the dog and moves it rearwardly thereby 95 drawing upon the link 7 to turn the knock-off lever as will be readily understood. The mechanism described constitutes a good form of transmission mechanism for accomplishing the desired object, and is substantially 100 the same as that shown and described in the patent to G. B. Ambler, Number 885,130, dated April 21, 1908, but any suitable train of mechanism may be employed for utilizing the arresting action of a drop wire due to a 105 warp fault to stop the loom.

The rocker 15 has secured thereto the arm 18 which is connected by a rod 19 with a transmission arm 20 secured to a rock-shaft 21 extending transversely of the loom. The 110

rock-shaft 21 is provided with an arm 22, Fig. 1, to which is connected the rock-shaft actuating rod 23 which extends downwardly and is connected at its lower end at 24 with 5 a follower or lever 25 pivoted at 26 to a stand 27. The follower 25 has an end portion 28 which rides upon the periphery of a cam 29 mounted on the shaft 30 which may conveniently be the under or cam shaft. The 10 follower 25 is under the influence of a spring 31, one end of which is connected to the outer portion of the follower at 32 and the other end of which is connected at a fixed point 33, the construction being such that under the 15 yielding influence of the spring 31, the end 28 of the follower will normally rest upon the cam 29. The rod 23 at its upper portion is provided with a collar 34 between which and the arm 22 is interposed a spring 35, 20 and the upper end of the rod 23 has a hooked portion 36 working in a suitable slot 37 of the arm 22, the construction being such that while the rod 23 may impart rocking movement to the rock-shaft 21 in both directions, 25 such rocking movement will be yieldable, so that the rock-shaft may be stopped in its rocking movement in either direction.

At each side of the loom frame is a bracket 38 (Figs. 2 and 3) which may be conveniently connected to the side frames of the loom adjustably, as by the foot portion 39 and a table bracket 40, the two being provided with suitable bolt and slot connections for adjustment, as indicated in Figs. 2 and 3.

35 The brackets 38, one at each side of the loom, support drop wire guides 41, four of said guides being shown in the present instance. The ends of the guides 41 preferably are received in slotted portions of the brackets 38 and are held detachably therein by cap-pieces 42 which overlie the ends of the guides and are held to the brackets by suitable bolts 43.

40 The drop wire guides 41 afford guiding means for the drop wires 44 which, in the present instance of the invention, are provided with elongated slots 45 through which the drop wire guides extend. The drop wires 44 are arranged in rows, as usual in warp stop motions, and are adapted to be supported by the warp threads α . As shown, the drop wires are provided with eyes or openings 46 which in the present instance are below the elongated slots 45, and through 45 the eyes 46 the warp threads α pass, preferably one thread through each eye.

46 The warp threads are supported by the rods 47 which extend transversely of the loom and are preferably supported by the 50 side brackets 38.

55 The feelers which cooperate with the drop wires are mounted upon feeler carriers, two of which form a unit of the warp stop motion, and the feelers are supported above 60 the plane of the warp threads for accessibil-

ity of parts and for ready removal from operative relation to the drop wires when it is desired to run the loom without stopping in response to a fault in the warp. In the present instance the two feeler carriers are 70 similar, and comprise the side members 48 between which extend the feelers 49, two being shown in the present instance of the invention. The ends of the feelers 49 are secured to the side members 48 by means 75 such, for instance, as screws 50, although any appropriate securing means may be employed. The side members 48 of each feeler carrier are connected by a rod 51 to which the side members may be adjustably secured 80 by set screws 52, Figs. 2 and 3.

85 Since the feelers are to be supported above the plane of the warp threads and the feeler carriers, together with the feelers, are to be removable from operative relation with the other elements of the warp stop motion when the loom is to be run without stopping in response to a warp fault, the side members of the feeler carrier are supported beyond the ends of the guide bars 41, the effect being 90 that either or both of the feeler carriers may be readily removed at will from operative relation with its rows of drop wires.

95 As one good means for supporting the feeler carriers beyond the ends of the drop wire guides, the side brackets 38 are provided with supporting guide-ways which permit the feeler carriers to be reciprocated toward and from each other. The guide-ways, in the present instance, are formed 100 by supporting flanges 53 which project outwardly from the side brackets 38, as best shown by Figs. 2 and 3, and upon the flange 53 ride the shoes 54 carried by the adjacent end portions of the side members 48 of the 105 feeler carriers, the construction being such that the feeler carriers may be readily lifted heightwise of the drop wires, as indicated in Fig. 3, to remove them from operative relation therewith.

110 The rock-shaft 21, hereinbefore described, is preferably supported in bearings carried by the side brackets 38, and in similar location with respect to the side brackets 38 is a second rock-shaft 55. Each of the rock-shafts 21 and 55 have extending therefrom the arm 56 formed with open or bifurcated ends 57 adapted to be detachably engaged with the end portions of the rods 51 extending between the side members of each of the 115 feeler carriers, when such feeler carriers are in operative position, as indicated in Fig. 1.

120 The rock-shafts 21 and 55 are connected for rocking movements in unison in opposite directions, and as a good form of means to this end each rock-shaft has extending therefrom an arm 58, one of which carries a pin 59 which operates in the bifurcated end portion 60 of the other arm, as indicated in Figs. 2 and 3, the construction being such that 130

upon rocking movement being imparted to one of the rock-shafts, as 21, through the mechanism hereinbefore described, such rocking movement is transmitted to the other 5 rock-shaft, but in the opposite direction, and the two feeler carriers are consequently given reciprocating movements in opposite directions.

When the drop wires are supported in 10 their raised position by normal warp threads, the two feeler carriers may partake of their reciprocating detecting movements toward and from each other, and the loom will continue to run. When, however, a warp thread 15 breaks or becomes too slack, the supported drop wire will drop, thereby bringing its widened or enlarged open portion, in the present instance, into the path of movement of the cooperating feeler, thereby arresting 20 the feeler and the two feeler carriers and effecting loom stoppage through the train of mechanism hereinbefore described.

When it is desired to run the loom without stopping in response to a fault in the 25 warp, the loom attendant may raise the two feeler carriers from their operative relation with the drop wires, as indicated in Fig. 3, thereby detaching the feeler carriers from their actuating means, and the loom may 30 continue to run until the attendant replaces the feeler carriers in operative position. Should it be desired to remove the warp from the loom with the drop wires and the drop wire guides, as is the case 35 when a new warp is to be drawn or tied in, the feeler carriers may be moved from their operative to their inoperative position or lifted as indicated in Fig. 3, whereupon the drop wire guides and drop wires may be 40 detached from the supporting side brackets and they, together with the warp, may then be taken into the drawing-in or tying-in machine.

What is claimed is:

45 1. In a warp stop motion for looms, the combination of a series of drop wires arranged in parallel rows, two feeler carriers, feelers supported by the feeler carriers above the plane of the warp threads, means for causing movements of the feeler carriers toward and from each other, and means for effecting loom stoppage when the movement of either feeler is arrested by a drop wire.

55 2. In a warp stop motion for looms, the combination of a series of drop wires arranged in parallel rows, drop wire guides, two feeler carriers each provided with a feeler for acting upon the drop wires in a 60 plane above the warp threads, and means for causing detecting movements of the feeler carriers and feelers simultaneously toward and from each other, and means for stopping the loom when one of the feelers is 65 arrested by a drop wire.

3. In a warp stop motion for looms, the combination of a series of drop wires arranged in parallel rows, a drop wire guide passing through the drop wires of each row, two feeler carriers each supporting a feeler 70 above the plane of the warp threads that the feelers may be removed from operative relation with the rows of drop wires by movement of the feelers heightwise of the drop wires, means for causing reciprocating 75 movements of the feeler carriers and feelers toward and from each other when in operative position, and means for stopping the loom when a feeler movement is arrested by a drop wire. 80

4. In a warp stop motion for looms, the combination of a series of drop wires arranged in parallel rows, drop wire guides, supports for supporting the end portions of the drop wire guides, two feeler carriers 85 having side members supported for reciprocating movements outside the drop wire guide supports, feelers extending between the side members of the feeler carriers above the warp threads, and means for reciprocating the two feeler carriers toward and from each other. 90

5. In a warp stop motion for looms, the combination of a series of drop wires arranged in parallel rows, drop wire guides, 95 brackets at opposite sides of the loom for supporting the drop wire guides, two feeler carriers having side members supported beyond the ends of the drop wire guide and having feelers which extend between the 100 side members of the carriers above the plane of the warp threads that the feeler carriers may be free for movement upwardly from operative position, and means for simultaneously reciprocating the feeler carriers 105 toward and from each other.

6. In a warp stop motion for looms, the combination of a series of drop wires arranged in parallel rows, drop wire guides, two feeler carriers, feelers carried thereby 110 above the plane of the warp thread, means for supporting and reciprocating the two feeler carriers beyond the ends of the drop wire guides constructed and arranged to permit the feeler carriers to be raised from 115 operative position when the loom is to be run without stopping due to a warp fault.

7. In a warp stop motion for looms, the combination of brackets adjustably secured to each side of the loom, drop wire guides 120 supported by the brackets, two feeler carriers supported by the brackets outside the end portions of the drop wire guides and carrying feelers which extend above the brackets and warp threads, means for imparting feeler detecting movements to the feeler carriers, and means for stopping the loom when the movement of a feeler carrier 125 is arrested by a drop wire.

8. In a warp stop motion for looms, the 130

- combination of brackets adjustably secured to each side of the loom, drop wires, drop wire guides supported by the brackets, two feeler carriers supported by the brackets 5 outside the end portions of the drop wire guides and carrying feelers which extend above the brackets and warp threads, a rock-shaft carried by the brackets, means for 10 rocking the rock-shaft, and connections between the rock-shaft and the feeler carriers for reciprocating the feeler carriers in opposite directions.
9. In a warp stop motion for looms, the combination of a bracket at each side of the loom, drop wires, drop wire guides supported by the brackets, two rock-shafts, two 15 feeler carriers, feelers mounted on the feeler carriers above the plane of the warp threads, connections between each rock-shaft and one of the feeler carriers, connections between 20 the rock-shaft which effect simultaneous movement of the feeler carriers toward and from each other, and means for rocking one of the rock-shafts.
- 25 10. In a warp stop motion for looms, the combination of brackets at each side of the loom, a series of drop wires arranged in parallel rows, two feeler carriers mounted
- outside the ends of the rows of drop wires, 30 feelers mounted on the feeler carriers above the plane of the warp threads, rock-shafts, extending transversely of the loom and each detachably connected to one of the feeler carriers for imparting reciprocating movements thereto, interengaging arms connecting the rock-shafts for causing simultaneous 35 reciprocating movements to be imparted to the two feeler carriers, and means for stopping the loom when one of the feelers is arrested by a drop wire. 40
11. In a warp stop motion for looms, the combination of two feeler carriers, a rock-shaft connected to one feeler carrier, a rock-shaft connected to the other feeler carrier, arms secured to the respective rock-shafts 45 and having a pin and slot connection for causing the feeler carriers to be moved simultaneously toward and from each other, a series of drop wires arranged in parallel 50 rows, and means for stopping the loom when one of the feeler carriers is arrested by a drop wire.

In testimony whereof, I have signed my name to this specification.

EDWARD S. STIMPSON.
